MARK E. FERNALD, OF SOUTHBORO, MASSACHUSETTS, ASSIGNOR TO C. C. BLAKE, INCORPORATED, OF BOSTON, MASSACHUSETTS, A CORPORATION OF NEW YORK.

LEADER-HOLDING APPARATUS.

Application filed March 4, 1922. Serial No. 541,246.

This invention relates to shoe making and more particularly to an apparatus for holding a leader accurately in position in a boring mill for the purpose of having drilled in 5 it the holes by which it is to be secured to the shoe jack with which it is to be used.

In making one type of shoe on automatic machinery a jack, on which the shoe is mounted, is secured to a leader which controls the movements of the jack in automatically performing the various shoe making operations necessary to bottom the shoe. This leader is of general sole-shaped form and is provided with a guiding flange. The 10 jack is mounted on the leader in such a position that the projections of the edge face of the insole of the shoe on the jack coincide with the inside face of the guiding flange. In order to secure the jack to the leader in 15 the relative position described, the jack is provided with a pair of expanding bushings located a fixed distance apart but having a definite relation to a predetermined imaginary datum line on the insole, whatever its 20 size or style may be, and the leader is provided with a pair of holes for receiving the bushings having the same relation to a like imaginary datum line on the leader.

The object of the present invention is to 25 provide an apparatus for holding leader blanks, of all sizes and styles, in such relation to two previously set drills of a drill press that when the holes for securing the leader in place are drilled and the jack secured to the leader, the inside face of the guiding flange will have the relation to the 30 edge of the insole of the shoe which is described above.

Accordingly a feature of the invention 35 comprises a leader holder having a removable member in which are seated a pair of thimbles forming guides through which the two drills of the drill press are to operate. These thimbles are spaced apart the fixed 40 distance which is common for the holes of all leaders. Below the thimble-carrying member is a leader supporting and centering device provided with adjustable gages by means of which a leader blank of any size or 45 style is so positioned relative to the drill thimbles, when the latter are superimposed on the blank, as to receive drill holes in such 50 a location relative to the ends of the blank

that, when bolted to the jack, the desired relation of the leader to the edge of the insole of the jacked shoe will be obtained.

To the accomplishment of this object, and such others as may hereinafter appear, as will readily be understood by those skilled in the art, the invention comprises the features and the combinations of parts herein-after described and then particularly pointed out in the appended claims.

The preferred form of the invention is shown in the accompanying drawings in 65 which Figure 1 is a longitudinal cross sectional view through the leader holding apparatus; Fig. 2 is a transverse cross sectional view on the line 2—2 of Fig. 1; Fig. 3 is a plan of the leader holding apparatus 70 with the cover removed, showing a leader in place; Fig. 4 is a plan view similar to Fig. 3 with the cover clamped in position ready for the drilling operation; Fig. 5 is a view in front elevation of the apparatus as shown 75 in Fig. 4; Fig. 6 is a plan in full size of a leader which has been drilled; and Fig. 7 is a longitudinal cross sectional view on line 7—7 of Fig. 6.

The purpose and use of the leader which 80 is to be drilled with the aid of the apparatus hereinafter to be described, will first be explained, referring more particularly to Figs. 6 and 7. In one mode of manufacturing welt shoes a shoe is mounted on a jack of the 85 saddle and spindle type, and a leader 10 is secured to the under side of the jack. This leader is provided with a guiding flange 12 and the jack is mounted on the leader so that the projections of the edge face of the insole 90 of the shoe on the jack coincide with the inside face of the guiding flange, except at the toe of the leader where there is a slight variation to allow for the box toe. If the box toe is considered, for purposes of illustration, as a part of the insole, then the projections of the edge face of the insole coincide with the inside face of the guiding flange entirely around the leader. The leader 10 carrying the jacked shoe is inserted 100 in an automatic machine in which the leader is actuated to transfer the point of operation of the welting or other shoe bottoming tools around the shoe. It will thus be apparent to those skilled in the art that the 105 inside face of the guiding flange 12 on the

leader 10 bears a definite relation to the edge face of the insole.

In assembling the leader, the lasted shoe, and the jack an imaginary datum line is selected, extending from toe to heel, which is the same for both shoe and leader and for all sizes and styles thereof. The insole of the shoe on the last has previously been marked, primarily for another purpose, at two points on this datum line each at an arbitrary, but the same, distance from opposite ends thereof. The shoe is so located on the jack support that these two points are equidistant from its center. The expanding bushings, or other leader clamping devices, are also equidistant from the center of the jack support and their centers lie in the vertical plane of the insole datum line. If now, the leader be clamped on the jack through bushing-receiving holes drilled on its datum line equidistant from the center of the leader, the inside face of the leader flange will necessarily lie in the vertical plane of projections of the edge face of the insole, as is desired.

It will be advantageous to describe first the required location, in accordance with the foregoing explanation, of the leader holes with relation to the area bounded by the leader flange; and then to describe the leader holder, forming the subject matter of the present invention, which is used to center all sizes and styles of leaders in the exact position beneath the drills to enable them to receive their holes in said required location.

Referring to Fig. 6, it will be assumed that parallel tangent lines $a-a$ and $b-b$ are drawn at the ends of the inner face of the flange 12 of the leader, which lines, in the last analysis, are normal to a plane containing both axes of the leader securing devices. Parallel lines $a'-a'$ and $b'-b'$ are drawn across the toe and heel portions, respectively, of the leader parallel to the lines $a-a$ and $b-b$ at an arbitrary distance therefrom, which in practice is $1\frac{1}{2}$ " for all sizes and styles. The portions of the lines $a'-a'$ and $b'-b'$ lying between the inside face of the flange 12 at either side of the leader are then bisected. The imaginary datum line upon which the leader holes are to be drilled passes through these central points indicated at c and d . The centers of the leader holes are equal distances from the center e of the line $c-d$. In practice the distance between the drills for all leaders is $6\frac{1}{4}$ ". It will be observed that with a small sized leader, such as is illustrated in Fig. 6, the leader holes 14 and 16 lie outside of the imaginary points c and d . With a leader of greater length than shown on Fig. 6, the fixed distance between the holes causes them to lie nearer to the points c and d , or within these points. The leader illustrated in Figs. 3 and 4 in

the drawings is one of the larger sizes, and in that instance, as will hereinafter be explained, the position of the leader holes is well within the imaginary points c and d .

Referring now to Figs. 1 to 5 the leader holder comprises a frame having a base block 18 and a hinged cover 20. At the rear edge of the base block rise two posts 22 which, together with two downturned lugs 24 at the rear of the cover, form the supports for the hinge pintle 26 which is secured to the cover by a pin 28 (Figs. 4 and 5). The cover has the shape shown in Fig. 4 its front edge being provided with two slots 30 for receiving the shanks of clamping bolts 32 which are threaded into posts 34 rising from the forward edge of the base block. Extending through the cover and spaced $6\frac{1}{4}$ inches from center to center are two thimbles 36 and 38 forming guides for two similarly spaced drills of a drill press. The construction and mounting of the drill thimbles will be fully understood from the cross-sectional views in Figs. 1 and 2. In using the leader holder the frame is placed in the drill press with the axes of its guiding thimbles in alignment with the axes of the drills (not shown).

The base block 18 is provided at each end with longitudinal dove-tail ways 38 and 40 in which are mounted slide blocks 42 and 44 (Fig. 5). The parts carried by these two slide blocks are alike and a description of one will suffice for both. The lower portion 46 (Fig. 2) of the slide block 42 is of dove-tail cross-section to fit the way 38 and supports a plate 48 which overhangs the way and bears on the surface of the base block 18. The plate 48 is provided with a transverse slot 50 at the sides of which are seated racks 52 and 54 having lugs at their outer ends which sustain leader grippers 56 and 58 respectively. Between the racks and meshing therewith is a pinion 60 mounted on the upper end of a vertical pin 62 received in a central bore 64 through the bottom of the slot 50 and extending into the portion 46. The lower end of the pin 62 is stepped loosely in a bearing at the bottom of the bore as fully shown on Figs. 1 and 2. The pinion is thus freely rotatable but it is continually urged to rotate in a direction to force the leader grippers outwardly by a torsion spring 66 secured to the block portion 46 and the under side of the pinion. Screwed to the upper face of the plate 48 is a leader supporting plate 68 having aligned transverse slots 70 through which the leader grippers project and the outer ends of which serve to limit the outward movement of the grippers under the influence of the spring 66.

It is essential that the centers of the pinion 60 in each of the slide blocks 42 and 44 be in the vertical plane of the centers of the

- drill thimbles 36 and 38 because the centers of these pinions correspond to the datum line points *c* and *d* referred to in the previous discussion. The pinions are mounted on 5 slide blocks because their distance apart will vary in accordance with the length of the leader to be drilled. Lines through the centers of the grippers 56 and 58 correspond to the imaginary lines *a'-a'* and *b'-b'* shown 10 on Fig. 6. Accordingly each slide block and referring now to the slide block 42 is provided with a leader gage 72 which overhangs the leader supporting plate 68 at the outer end thereof and has an inner straight gag- 15 ing edge 73 parallel to the center line of the leader grippers and situated $1\frac{1}{2}$ inches therefrom. Hence the gages correspond to the imaginary tangent lines *a-a* and *b-b* shown on Fig. 6.
- 20 Equal and opposite adjustment of the leader supporting slide blocks is obtained through the leverage shown best in Fig. 3. An operating handle 74 is pivoted at 76 on the base block 10 midway between the pin- 25 ions 60 and like links 78 and 80 connect this lever to the slide blocks. The links extend from pivotal points on the longitudinal center line of each slide block to pivotal points on the lever equidistant from its pivotal 30 connection to the base block. A movement of the handle 74 will actuate the slide blocks in their ways and cause the pinion centers to move in the vertical plane of the drill axes, or along a path indicated by the datum line 35 *c-d* shown on Fig. 6.
- In using the leader holder the cover 20 is thrown back, the slide blocks opened and a leader placed thereon by engaging its flange 12, at one side, with the two grippers 40 56 and pulling them inward in their slots 70, against the pressure of the spring 66 until the other two grippers 58 have been drawn inward sufficiently to bear against the flange 12 at the other side of the leader. It 45 will be observed, see Figs. 2 and 3, that the grippers are formed with angular leader flange engaging ends to provide a line bearing. The handle 74 is now operated to determine the distance between the gage 72 50 and bring their inner edges 73 tangent to the inner face of the leader flange 12 at the heel and toe of the leader. The springs 66 permit the leader grippers to yield in or out as may be necessary during this movement 55 of the gages. Since the gages on one side move equally and oppositely to those on the other side the leader in its final position is centered transversely relative to the imaginary datum line hereinbefore referred to 60 and consequently to the drill thimbles and drills which operate therethrough.
- Having positioned the leader both longitudinally and transversely the cover 20 is superposed on the base block and the leader
- is held in position by means of clamps sus- 65 tained by the cover. These clamps comprise pivoted levers 82, in pairs, above the toe and heel portions of the leader and are severally pressed against the leader flange each by means of a co-operating screw 84 (see 70 Fig. 2).
- It will be observed that a use of the leader holding apparatus insures that the $6\frac{1}{4}$ inch spaced drill holes will always have their longitudinal center line coinciding with the 75 imaginary datum line *c-d* of Fig. 6 and will be equally spaced from the center of the leader. Hence all leaders will, when secured to the jack, be so positioned, both longitudinally and transversely, relative to the 80 shoe being operated upon as to bring the outline of the inner face of the leader flange vertically below the edge of the insole of the shoe.
- Those skilled in the art of shoe making 85 will readily perceive that the field of use of the apparatus described is not limited to the single operation of drilling leaders but includes within its scope the marking of the leader by other tools than drills operating 90 through the thimbles on the cover, and the substitution of a shoe sole, shoe last or similar article as the piece to be positioned and marked, without inventive change in its construction or principle of operation. In the 95 following claims the term "leader" is used in the inclusive sense indicated by the above statement of the scope of the invention.
- While it is preferred to employ the specific construction and arrangement of the 100 parts shown and described, since this construction and arrangement is the simplest and most efficient embodiment of the invention which has yet been devised, it will be understood that this construction and arrangement is not essential except so far as it is specified in the claims, and may be varied or modified without departing from the broader features of the invention.
- 105
- What is claimed as new is:
- 110
1. A leader holding apparatus comprising two pairs of leader gripping-jaws, the jaws of each pair being movable equally and oppositely from a central point between them, an end gage associated with each pair of jaws at a predetermined fixed distance from a line drawn through said associated jaws, and means for moving said end gages simultaneously and equally toward and from a central point.
- 115
2. A leader holding apparatus comprising two pairs of leader gripping-jaws, the jaws of each pair being movable equally and oppositely from a central point between them, an end gage associated with each pair of jaws at a predetermined fixed distance from a line drawn through said associated jaws, 120 a pair of movable blocks supporting each a
- 125

pair of jaws and their associated gage, and means for adjusting the distance between said blocks.

3. A leader holding apparatus comprising heel and toe gages adjustable to receive different sized leaders between them, and means movable with each gage for holding a leader in position between said gages.

4. A leader holding apparatus comprising heel and toe gages to receive a leader between them, leader gripping devices associated with each gage at a predetermined

fixed distance therefrom, and a separate support for each gage and its associated gripping devices.

5. A leader holding apparatus comprising two blocks for sustaining the ends of a flanged leader, a gage on each block overhanging the leader for registering the location of the ends of the leader flange on the blocks, and means bearing on the inner surface of the leader flange for seating the leader in such registered position.

MARK E. FERNALD.
